UNITED STATES PATENT OFFICE.

HERMAN DOMMER AND JOHN DOMMER, OF CHICAGO, ILLINOIS.

CLAMPING DEVICE FOR SLIDING DOORS.

1,117,643.

Specification of Letters Patent.

Patented Nov. 17, 1914.

Application filed March 9, 1914. Serial No. 823,504.

To all whom it may concern:

Be it known that we, HERMAN DOMMER and JOHN DOMMER, citizens of the United States, residing at Chicago, in the county of Cook and State of Illinois, have invented certain new and useful Improvements in Clamping Devices for Sliding Doors, of which the following is a specification.

The present invention relates to clamping devices for sliding doors, and is particularly designed for use on freight cars having doors which are suspended from a track at the top, the lower end of the door being confined by means of guide brackets. It frequently happens that in this type of doors the freight settles against the door during a trip, and causes it to bind against the guide brackets, which makes it very difficult to slide the door open. It is the object of the invention to overcome this difficulty by providing a clamping device of simple construction which securely holds the door during a trip, and which is adjustable to release the door and allow the same to be easily opened.

For a complete understanding of the invention, reference is had to the accompanying drawing wherein—

Figure 1 is a front elevation showing the application of the invention; Fig. 2 is a section on the line 2—2 of Fig. 1, and Fig. 3 is a horizontal section on the line 3—3 of Fig. 2.

Referring specifically to the drawing, at 10 is shown a door slidably suspended from a track 11 mounted on the side of a freight car. To the sill 12 are secured the clamping devices which form the subject matter of the present invention. Two clamping devices are shown, but it is obvious that the number may be varied to suit different conditions. Each clamping device consists of a bracket 13 provided with an outstanding bolting flange 14 whereby it is secured to the sill 12. The outer portion of the bracket is provided with an upstanding lug 14^a which limits the outward swing of the door. The bracket is recessed from the top to the bottom, and in said recess is located a clamping member 15, swinging laterally with respect to the door, the lower end of which member is secured to the corresponding portion of the bracket by a pivot pin 16. The upper end of the clamping member extends up above the top of the bracket and has an enlarged portion or jaw 17 adapted to engage a bracket 17^a

mounted on the outer side of the door and extending below the same. The lug 14^a is provided with a recess 18 to accommodate the jaw portion 17 of the clamping member 60 when the latter is swung out to release the door.

The clamping member 15 is provided with a slot 19 extending obliquely in an outward and upward direction from a point near the pivot pin 16. The upper end of the slot terminates in a short inward bend 20. A roller 21 carried by a slotted rocker arm 22 works in the slot 19. A shaft 23 is journaled in the brackets 13, and the rocker arms 70 of both clamping devices are secured to said shaft. The shaft is square in cross-section and provided with flanged bearing rings 23^a. One end of the shaft 23 is provided with an operating lever 24. The lever is pivoted to 75 the shaft as shown at 25 in order to permit it to be swung out of the way when the clamping device is released.

By swinging the lever 24 up against the side of the car, the rocker arms 22 are swung 80 to a substantially horizontal position, the rollers 21 riding up the oblique slots 19 and forcing the clamping members 15 against the brackets 17^a. In this position the rollers rest in the inward bends 20 at the upper 85 ends of the slots, and there is no tendency of the rollers to ride down the slots. The lever 24 may be sealed to the side of the car. When the door is to be opened, the lever 24 is swung out from the car, causing the rollers 21 to ride down to the lower end of the slots 19 and swing the clamping member 15 away from the bracket 17^a until the jaw portion 17 rests in the recess 18 in the lug 14^a. Then the door is free to be swung out 95 slightly and may be easily slid open.

The shaft 23 forming the pivot of the rocker arms 22 is located between the sill 12 and the intermediate portion of the clamping members 15, whereby the structure is 100 placed close to the sill, and rendered more compact than would be possible otherwise, and there are no parts on the car projecting therefrom an excessive distance.

We claim:

1. The combination with a sliding door and a sill, of a bracket mounted on the sill, a door clamping member pivoted to the bracket and operating laterally of the door, said member having an oblique slot, a rock 110 shaft carried by the sill and located between the sill and the intermediate portion of the

clamping member, a rocker arm on said shaft, means carried by the rocker arm and working in the oblique slot for swinging the clamping member, and means for operating

5 the rock shaft.

2. The combination with a sliding door and a sill, of a bracket mounted on the sill, a door clamping member pivoted to the bracket and operating laterally of the door, 10 said member having a slot extending obliquely upward and outward with respect to the sill and terminating in an inward bend, a rock shaft carried by the sill and located

between the sill and the intermediate portion of the clamping member, a rocker arm 15 on said shaft, means carried by the rocker arm and working in the oblique slot for swinging the clamping member, and means for operating the rock shaft.

In testimony whereof we affix our signatures in presence of two witnesses.

HERMAN DOMMER.
JOHN DOMMER.
